INTERNAL-COMBUSTION ENGINE
CONDITIONING COMPOUNDS

Raymond I. Potter, Lorain, and Harry Gillett,
Hudson, Ohio, assignors to The Standard Oil
Company, Cleveland, Ohio, a corporation of
Ohio

No Drawing. Application September 25, 1946,
Serial No. 699,350

6 Claims. (Cl. 252—170)

1

Internal combustion engines are commonly flushed out and cleaned with a petroleum distillate before being replenished with fresh lubricating oil. This mechanically washes the old oil off of the metal surfaces and slushes out loose sludge material, but it has little ability to remove coated-on deposits, its solvent power being insufficient. The chemical composition of engine deposits and coatings is not known. There is reason to believe though that some residual materials from fuels, and more materials having unsaturated bonds formed by pyrolytic action in lubricating oils, take up oxygen somewhat in the nature of the action which occurs in oxidation of paint oils. The conditions in engine operation are highly favorable to oxidation, and the metal surfaces act catalytically; and at any rate a tenacious varnish-like coating is commonly formed on piston skirts and in recesses and on surfaces not subject to mechanical rubbing. Such oxygen-containing compounds are insoluble in hydrocarbon type solvents, and from this standpoint it can be realized that no amount of washing with hydrocarbon distillates can accomplish cleaning. We have now found, however, that a composition as set forth hereinafter is able to exert a substantial dissolving and cleaning action on such coated-on deposits in engines, including conditions involving ring-sticking, etc.

Other objects and advantages of the invention will be apparent from the following description.

To the accomplishment of the foregoing and related ends, the invention, then, comprises the features hereinafter fully described, and particularly pointed out in the claims, the following description setting forth in detail certain illustrative embodiments of the invention, these being indicative however, of but a few of the various ways in which the principle of the invention may be employed.

To make up our compound, we employ an ether and a hydrocarbon in compatible combination. For this, the ether is sufficiently high boiling to not be fugitive under the conditions in which the compound must be used, i. e. in an engine which generally has not cooled down from its operating state. This ether is a glycol mono-ether, and may be of the group of glycolmono-methyl ether, glycolmonoethyl ether, glycolmonobutyl ether, glycolmonobenzyl ether, and beta hydroxyethyl phenyl ether, and all these are hereinafter referred to concisely as "glycol mono-ethers." Ordinarily we prefer the glycolmonobutyl ether. This and the glycolmonoethyl

2

ether are in general particularly desirable; that is, a glycolmono-alkyl ether in which the alkyl has at least two carbon atoms and not more than four. And, with the glycol ether we mix a hydrocarbon distillate.

The relative proportions of the glycol ether and the hydrocarbon distillate may vary somewhat, depending upon particular conditions to be encountered, and while in many cases equal parts are desirable, in other instances we may apply a smaller proportion of the ether from 50% down to about 10%. This is a practical range of proportions for good results, and variations therefrom are generally not desirable, as amounts down to one per cent for instance are less effective, and amounts materially about fifty per cent may be of undesirably low flash point especially if one of the lighter glycol compounds be used.

20 These particular components are, as aforesaid, highly compatible with each other to a homogeneous stable composition, and the preparation of the material requires merely an adequate mixing together of a stated proportion of the ingredients.

25 In use, while a fouled engine for instance which is to be treated may be drained of the old oil, and a charge of our treating compound be introduced into the crank case, it is not however necessary to drain the crank case prior to flushing.

30 Thus the flushing solution may be added directly to the old oil in the crank case. It is beneficial to add a quantity of liquid in the crank case during the flushing operation greater than the amount of oil normally present. The quantity of liquid for the flushing operation may desirably be about twice that of the normal operating volume of lubricating oil. For instance, with an ordinary five-quart crank case, about five 35 quarts of flushing solution may be added to the oil already present, making a total of ten quarts of liquid for the flushing operation. Or, if the crank case be drained first, preferably more than five, and up to ten or more quarts of flushing 40 solution may be put in for the treating operation.

45 The upper limit or quantity of flushing mixture is set only by the ultimate capacity of the crank case. In general, the amount of total solution may be 2 to 2.5 times the normal crank case 50 capacity. The flushing solution having been supplied to the engine, the engine is then operated at a fast idling speed for a sufficient length of time to raise the temperature of the flushing solution to at least 150° F., or up to around about 55 175° F., the solution thus being thoroughly

flushed over metal surfaces and through the recesses and passage-ways of the moving parts, after which the engine is stopped, the crank case is drained, and may be re-filled with fresh oil.

We have found that it is desirable for optimum cleansing action to keep the viscosity of the entire mixture in the crank case during the treating operation below about 250 SUS at 100° F. Thus, if the crank case is drained of old oil prior to the flushing operation, the viscosity of the flushing solution should not exceed 250 SUS at 100° F. Where however the flushing solution is added directly to the old oil in the crank case, the viscosity of the solution so added should be such that the total mixture in the crank case will fall within the desired viscosity range. The lower ranges of viscosity for the hydrocarbon distillate will be dictated by the boiling range of the stock, which should be sufficiently high to avoid undue loss through evaporation during the flushing operation. Accordingly, the mineral oil distillate may be taken from a range of kerosene up through the lubricating stocks, provided the afore-stated conditions be complied with.

As an example:

About five quarts of a mixture of ten per cent glycolmonobutyl ether in absorbent oil (a fraction just above kerosene, boiling between about 450 and 750° F., having an API gravity of 30-35° and viscosity of 50 SUS at 100° F.) is added to the old oil in the crank case, and the engine is idled rapidly for about 30 minutes, then is stopped, and the crank case is drained, ready for a charge of new oil.

As illustrating the action of our compounds, the following laboratory tests may be noted. With a test apparatus including a reservoir heated at a temperature of 170-180° F., and a container thereabove holding test pieces of sludge or "varnish" coated metal which are flooded with the solution pumped from the heated reservoir, so that the solution flows over the coated metal sample, with coated metal pieces flooded thus for thirty minutes with a hot mixture of equal parts of absorbent oil and 300 red oil lubricating stock, as a control, no sludge or varnish was removed from the coated test plate, but when similarly a mixture of fifty per cent 300 red oil and forty per cent absorbent oil and ten per cent glycolmonobutyl ether, was heated and pumped over a like coated test plate for 30 minutes, a very large percentage of the sludge coating was dissolved off and removed from the test plate. To attack varnish-like sludge coatings thus, the solvent character of the material is an important criterion as regards its effectiveness.

Other modes of applying the principle of the invention may be employed, change being made

as regards the details described, provided the features stated in any of the following claims or the equivalent of such be employed.

We therefore particularly point out and distinctly claim as our invention:

- 5 1. An internal combustion engine conditioning compound, consisting of glycolmonobutyl ether 10-50 per cent, and absorbent oil boiling between about 450 and 750° F. and having an A. P. I. gravity of 30-35° and viscosity about 50 SUS at 100° F.
- 10 2. An internal combustion engine conditioning compound, consisting of glycolmonobutyl ether 10-50 per cent and a hydrocarbon distillate substantially unvolatilized at crank case temperature.
- 15 3. An internal combustion engine conditioning compound, consisting of a glycolmonoethyl-ether 10-50 per cent, and absorbent oil boiling between about 450 and 750° F. and having an A. P. I. gravity of 30-35° and viscosity about 50 SUS at 100° F.
- 20 4. An internal combustion engine conditioning compound, consisting of a glycolmonobenzyl-ether 10-50 per cent, and a hydrocarbon distillate substantially unvolatilized at crank case temperature.
- 25 5. An internal combustion engine conditioning compound, consisting of 10-50 per cent of a glycolmonoalkyl ether in a hydrocarbon distillate substantially unvolatilized at crank case temperature, the alkyl group of such ether having at least two carbon atoms and not over four.
- 30 6. An internal combustion engine conditioning compound, consisting of 10-50 per cent of a glycolmono-ether of the class consisting of glycolmonomethyl ether, glycolmonoethyl ether, glycolmonobutyl ether, glycolmonobenzyl ether and beta hydroxyethyl phenyl ether in a hydrocarbon distillate substantially unvolatilized at crank case temperature.
